ELECTRONIC TUBE BASE AND THE LIKE

Richard L. Elliott, Sidney, N. Y., assignor to Bendix Aviation Corporation, New York, N. Y., a corporation of Delaware

Application May 28, 1949, Serial No. 96,119

4 Claims. (Cl. 173—361)

1

This invention relates to electrical apparatus and more particularly to means for combining electronic tubes and the like with the base and terminal prongs therefor.

One of the objects of the present invention is to provide mounting means in novel combination with the glass, metallic or other type envelopes of electronic tubes or the like which results in an ultimate product having numerous advantages over corresponding present-day products of the same type.

Another object of the invention is to provide an electronic tube or the like combined with terminal prongs in a novel manner to withstand a greater amount of rough handling and of vibration for a longer period of time than similar devices heretofore produced.

Still another object is to provide a device of the above character which may be produced by fewer manufacturing steps and at lower cost than has been heretofore considered possible.

A further object is to provide a novel plug-in type of electronic tube construction wherein the base which supports the terminals and the envelope prevents the entrance of moisture and hence reduces the danger of failure caused in known constructions by the lowering of the electrical resistance between the terminals when moisture is present.

A still further object is to provide an electronic tube of the above character which is admirably adapted for use in ignition systems of combustion engines on aircraft where the same are subjected to rough usage, to material vibration, and to wide and sudden changes of temperature and pressure during normal use.

The above and further objects and novel features of the invention will more fully appear from the following detail description when the same is read in connection with the accompanying drawings. It is to be expressly understood, however, that the drawings are for the purpose of illustration only and are not intended as a definition of the limits of the invention, reference for this latter purpose being had primarily to the appended claims.

In the drawings, wherein like reference characters refer to like parts throughout the several views,

Fig. 1 is a side elevation view, with parts broken away and partly in section, of one form of device embodying the invention;

Fig. 2 is a bottom view of the device of Fig. 1; and

2

Fig. 3 is a detail sectional view through one of the terminals of said device.

The single embodiment of the invention illustrated in the drawings, by way of example, is in the form of an electronic tube comprising an envelope 10 of glass or other suitable material. The internal construction of the tube has not been shown since it, per se, does not constitute a part of the invention and may take a great many different known forms. As an example, the invention has been successfully applied to the type of cold cathode tube known as a strobotron. If a metallic envelope is employed the lower end thereof is preferably sealed with a glass seal to isolate the interior of the tube. The invention may also be applied to tubes having a terminal at the upper end thereof.

The internal elements of the tube, such as the cathode, plate, grids, and the like, are connected in the usual known manner by means of flexible wire connectors 11 to rigid, preferably cylindrical, prong terminals 12. The latter may be tubular so that the wires 11 will extend therethrough for connection to the lower or outer ends thereof by any suitable means, such as by soldering. The terminals or plugs 12 are adapted for insertion in corresponding recesses or sockets in a socket member (not shown) of any known construction. It is desired, the terminals 12 may be solid rather than hollow and the wires 11 may be connected with the upper or inner ends thereof.

Novel means are comprehended by this invention for the purpose of mounting the envelope and terminal prongs in fixed relation to each other, whereby the tube is cushioned against shock and vibration and protected against failures caused by moisture and temperature changes. Said means also makes the construction easier to manufacture at lower cost. In the form shown in the drawings, said means consists of a cast base or mounting member 14 which may be applied to the other parts in a mold in liquid or plastic form and thereafter permitted to set to a relatively firm, yet resilient solid form through chemical reaction which may be and preferably is accelerated by the application of heat. Preferably a compound is chosen which will shrink slightly during the setting or curing process to insure a firm grip on the envelope and terminal plugs or prongs.

One material which has been found well suited for carrying out the present invention is known as Scintilla compound No. 115. It comprises a styrene polyester casting resin mixed with an organic peroxide catalyst whereby polymeriza-

tion of the resin is effected. Suitable resins of the above type are commercially available and lauroyl peroxide makes a suitable catalyst therefor.

The molding or casting of the base 14 may be effected under pressure or vacuum so that the compound will enter the hollow terminals 12 around wires 11 and the recess in the bottom of envelope 10. The curing or setting of the compound may be effected by the application of heat in a suitable oven at a sufficiently slow rate and for a suitable length of time to avoid cracking of the particular compound used. These factors will of course differ with different specific compositions used as molding material. Curing is preferably effected to the point that the material is firm when at room temperature and yet capable of yielding resiliently when, for example, a side pressure is applied to one of the terminals 12 or to the envelope 10. When the structure is used on a combustion engine, for example, and is subjected to high heat during operation, the material of base 14 will soften slightly and thereby increase the cushioning effect and avoid any danger of cracking due to vibration or other shock.

If desired, either the terminal prongs or envelope or both may be provided with irregularities, such as fins or corrugations, in the regions where the same are engaged by the base 14. The terminals may also be flared at the top or inner ends to facilitate insertion of the wires 11 and entry of the compound. In order to provide even greater protection for the envelope, the molded compound 14 may be extended around the remainder of the envelope preferably in the form of a thin coating 15 (illustrated by construction lines in Fig. 1) which may be integral with the base 14. Each terminal 12 may have a rib 16 which acts as a stop to determine the limit of movement of the terminal into a socket.

There is thus provided a novel construction for electronic tubes or the like which results in an expansion in the field of use of such tubes and makes the same available at lower cost. Additionally, tubes constructed in accordance with the novel method above described will have a greater useful life under comparable circumstances than similar tubes heretofore available. Said novel method may be advantageously carried out with the casting material and the other elements of the structure at room temperature or at a sufficiently low temperature to obviously prevent any ill effects therefrom. The base or support may also be cast without the application of pressure beyond normal atmospheric pressure or any pressure which might be detrimental. Similar structures which have been heretofore produced by molding have employed materials which required substantial heating and the application of considerable pressure during the molding operation.

Although only a limited number of embodiments are shown in the drawing and suggested

in the foregoing specification, it is to be expressly understood that the invention is not limited thereto. For example, changes may be made in the design and arrangement of the parts illustrated, as well as in the materials specifically mentioned, without departing from the spirit and scope of the invention, as it will now be understood by those skilled in the art. For a definition of the limits of the invention, reference is had primarily to the appended claims.

What is claimed is:

1. An electronic tube or the like comprising a hollow envelope, at least one flexible electrical conductor emerging from said envelope, a rigid hollow terminal pin receiving said conductor and being electrically connected therewith, and a unitary support of resilient insulating material cast around said conductor, an end portion of said pin, and at least a portion of said envelope and within said terminal around said conductor.
- 15 2. In a device of the class described, an envelope, an electrical conductor emerging from said envelope, a hollow terminal pin receiving said conductor and electrically connected thereto, and a unitary solid mass of resilient insulating compound filling the space in said terminal around said conductor and encompassing an end portion of said pin and at least a portion of said envelope to support the same in assembled relation.
- 20 3. A device of the class described comprising a hollow envelope, conductors emerging therefrom, hollow terminal pins receiving and connected to said conductors, and a resilient insulating material completely surrounding said envelope, end portions of said pins, and said conductors and filling said pins around the conductors therein.
- 25 4. An electronic tube or the like comprising a hollow envelope having an external recess in one end thereof, electrical conductors emerging from said envelope through said recess, hollow rigid terminal pins electrically connected to said conductors, and a yieldable unitary supporting base filling said recess, surrounding adjacent ends of said envelope and pins and said conductors therebetween and filling said pins around said conductors.
